2 SHEETS--SHEET 2.

UNITED STATES PATENT OFFICE.

EDWARD C. MEIER, OF PHOENIXVILLE, PENNSYLVANIA.

REAMING-TOOL

1,158,825.

Specification of Letters Patent.

Patented Nov. 2, 1915.

Application filed March 29, 1915. Serial No. 17,762.

To all whom it may concern:

Be it known that I, EDWARD C. MEIER, a citizen of the United States, residing at Phoenixville, in the county of Chester and 5 State of Pennsylvania, have invented certain new and useful Improvements in Reaming-Tools, of which the following is a specification.

My invention relates to improvements in 10 reamers, and more particularly to an improved multiple drilling and reaming tool, the object of the invention being to provide a tool of the character stated which will simultaneously drill and ream two holes in 15 proximity to each other, and which is especially designed for use in the formation of hand hole plates in the water legs of boilers.

A further object is to provide an improved 20 construction of tool in which parallel drill spindles are driven by a pinion which imparts motion to two idlers, and the latter in mesh with gears on both drill spindles, whereby the centers of the drill spindles can be located relatively close to each other, and 25 a maximum of power utilized in the driving operation.

With these and other objects in view, the 30 invention consists in certain novel features of construction and combinations and arrangements of parts as will be more fully hereinafter described and pointed out in the claims.

In the accompanying drawings: Figure 1 is a view in longitudinal section illustrating 35 my improved tool. Fig. 2 is a plan view of the drill with the upper half of the tool casing removed. Fig. 3 is a fragmentary view in longitudinal section at right angles to Fig. 1, the view being taken on the line 40 3—3 of Fig. 1, and Fig. 4 is a fragmentary view on a reduced scale illustrating the hand hole sheet of a boiler water leg to illustrate one use to which the tool may be put.

1 represents the drill casing which is 45 formed of two separable members 2 and 3 secured together by bolts 4 and nuts 5.

The lower member 3 of casing 1 supports 50 parallel drill spindles 6, which turn in bushings 7, and are provided with bearings 8 in their upper ends receiving journal pins 9 which are screwed into threaded sockets 10 in upper member 2, and lens bearings 36 are located in the ends of the bearings 6

between the same and the journal pins 9 to sustain the thrust of the tool. 55

The spindles 6 are provided with sockets 11 in their lower ends to receive drills 12, and while my invention is not limited to any particular construction of cutting tool, I preferably employ a combined drill and 60 reamer so that the hole which is made is reamed in the operation of drilling.

Between the spindles 6, a pin 13 is located and is provided with a screw-threaded upper end 14 engaging in a threaded socket 15 in 65 the lower member 3 of drill socket 1, and is provided with an annular flange 16 to bear against the lower face of the casing. This pin 13 is longer than the drills 12, and operates to properly position the drills as will 70 be hereinafter explained.

The upper member 2 of casing 1 is provided with a central opening 17 in which a bushing 18 is located, and a drive shaft 19 is mounted in the bushing and at its 75 lower end has keyed thereto a driving pinion 20.

A washer 21 is preferably interposed between the pinion 20 and the lower end of the bushing 18, and on this washer the casing is supported when idle, but when in operation, the downward pressure on the drive shaft 19 spaces the pinion 20 from bushing 18, so that there is a minimum of friction in the driving operation. 80 85

A shank 22 is secured by a screw 23 to the drive shaft 19, and is spaced from the upper end of the casing by ball bearings 24. The drive pinion 20 is located centrally in the casing, and meshes with two relatively long 90 idle gears 24, the journals 25 of which are mounted in bearings 26 in the upper and lower members 2 and 3 respectively of casing 1.

The idle gears 24, at their lower portions, 95 mesh with gear wheels 28, which latter are keyed to the upper ends of the drill spindles 6, and as shown clearly in the plan view, Fig. 2, the idle gears 24 mesh with both of the gears 28, and hence a firm, compact, strong and rigid power transmission is had to drive the spindles in the same direction and permit their location to be relatively close to one another. 100

While, of course, my invention is not limited to any particular manner of lubricat- 105

ing the several bearings, I have shown lubricant ducts 29 in the upper member 2 of the casing 1 which extend down through the journals 9 to lubricate the bearings 8 and also other parts of the tool.

5 My improved tool above described is capable of a wide range of usefulness, but is especially adapted for use in the formation of hand tools such as set forth in my application for patent executed on even date here-with, and in Fig. 4 I illustrate the manner of forming the holes.

A multiple punch is first used to punch the three holes 30, 31, and 32 in the plate 33. 15 These holes are in alinement, and the holes 30 and 32 are appreciably larger than the central hole 31. My improved drill above described is then used, and in operation the pin 13 is located in the hole 31, and the tool turned until the reamers 12 are in the holes 30 and 32. The tool is then operated. 20 The turning of shaft 19, through the medium of pinion 20, gears 24, and gears 28, impart rotary motion to the spindle 6, so that the holes 30 and 32 are reamed to a diameter indicated by the dotted lines 34. The tool is then removed, and another reamer used to 25 cut an opening indicated by the dotted lines 35, to complete the hand hole in the boiler plate.

30 While my invention is of course, not limited to any particular means for driving the tool, it may be connected with a source of power to turn the same, and when the drill is not in use, the casing will turn idly with the shank 22, but as soon as the turning movement of the casing is stopped by placing the hand thereupon, the spindles 6 will begin to revolve, and the tool perform its 35 normal operation.

40 While I have illustrated the tools 12 as reamers, I would have it understood that my invention broadly covers any cutting tool, and hence in the claims where I shall herein-after use the word "drill," I would have it understood that I use the same in its broad- 45 est sense.

Various slight changes might be made in the general form and arrangement of parts 50 described without departing from my invention as defined by the scope of the claims, and hence I do not limit myself to the precise details set forth, but consider myself at liberty to make such changes and alterations 55 as fairly fall within the spirit and scope of the appended claims.

Having thus described my invention, what I claim as new and desire to secure by Letters Patent is:

60 1. The combination with a support, of a pair of drill spindles located relatively close to one another, and a guide pin longer than the spindles and located between the spindles, substantially as described.

65 2. The combination with a casing, of paral-

lel drill spindles mounted to turn in the casing, and a guide pin longer than the spindles and secured in the casing and located between the spindles, substantially as described.

3. The combination with a casing, of parallel drill spindles mounted to turn in the casing, and a guide pin secured in the casing and located between the spindles, said guide pin projecting below the ends of the tools carried by the spindles, substantially as described.

4. The combination with a casing, of parallel drill spindles mounted to turn in the casing, a guide pin longer than the spindles and secured in the casing and located between the spindles, and means for simultaneously turning the spindles in the same direction, substantially as described.

5. The combination with a two part casing, of parallel drill spindles mounted to turn in one part of the casing, a guide pin longer than the spindles and secured to the casing between the spindles, a drive shaft mounted to turn in the other part of the casing, and gearing between the two parts of the casing connecting the drive shaft and the spindles, substantially as described.

6. The combination with a casing, parallel drill spindles in the casing, a guide pin longer than the spindles and secured to the casing between the spindles, a drive shaft in the casing, gears secured to turn with the spindles, a pinion secured to the drive shaft, and idle gears meshing with both spindle gears and also with the pinion, substantially as described.

7. The combination with a two part casing, of parallel drill spindles mounted to turn in one part of the casing, a drive shaft mounted to turn in the other part of the casing, and gearing between the two parts of the casing connecting the drive shaft and the spindles, and a guide pin located centrally between the spindles secured to the casing and projecting below the tool supported by the spindles, substantially as described.

8. The combination with a casing, parallel drill spindles in the casing, a drive shaft in the casing, gears secured to turn with the spindles, a pinion secured to the drive shaft, idle gears meshing with both spindle gears and also with the pinion, and a guide pin located centrally between the spindles secured to the casing and projecting below the tool supported by the spindles, substantially as described.

9. The combination with a casing, of parallel spindles supported in the casing, gear wheels secured to the spindles in the casing, a drive shaft projecting into the casing, a pinion on the drive shaft located in a plane above the spindle gears, and idle gears at opposite sides of the pinion meshing with

the pinion and with both of the spindle gears, substantially as described.

10. The combination with a two part casing, devices securing the two parts of the casing together, journal pins secured in one part of the casing, drill spindles mounted to turn in the other part of the casing and having bearings in their ends receiving the journal pins, gears secured on the spindles in the casing, a drive shaft extending through one part of the casing, a pinion on the drive shaft in the casing, idle gears con-

necting the pinion with the spindle gears, and a shank secured to the outer end of the drive shaft and having rotary mounting on 15 the casing, substantially as described.

In testimony whereof I have signed my name to this specification in the presence of two subscribing witnesses.

EDWARD C. MEIER.
